UNITED STATES PATENT OFFICE.

JOHN H. HUNT AND WILLIAM A. CHRYSST, OF DAYTON, OHIO, ASSIGNEES TO THE DAYTON ENGINEERING LABORATORIES COMPANY, A CORPORATION OF OHIO.

INDUCTION COIL.

Original application filed December 22, 1917, Serial No. 208,369. Divided and this application filed September 23, 1918. Serial No. 255,257.

To all whom it may concern:

Be it known that we, JOHN H. HUNT and WILLIAM A. CHRYSST, citizens of the United States of America, residing at Dayton, county of Montgomery, State of Ohio, have invented certain new and useful Improvements in Induction Coils, of which the following is a full, clear, and exact description.

10 This invention relates to ignition equipment for multi-cylinder engines, and, more particularly, for engines used in aviation work where maximum efficiency, lightness of weight and compactness of arrangement are required. Among the objects of invention, the following are enumerated.

20 To provide an improved ignition coil which is exceedingly simple and compact in design, light in weight, and reliable in operation; and one wherein the various parts are readily accessible for repairs or adjustments.

25 It is also an aim of the present invention to concentrate the magnetic field of the coil to as great a degree as possible, and to prevent losses in the magnetic field.

30 Further objects and advantages of the present invention will be apparent from the following description, reference being had to the accompanying drawings, wherein a preferred embodiment of the present invention is clearly shown.

35 The present invention has been described in our copending application Serial No. 208,369, filed December 22, 1917, of which the present application is a division.

In the drawings:

40 Fig. 1 is an end view of the induction coil, the distributor head and related parts being shown in section;

Fig. 2 is a plan view of the induction coil attached to its mounting;

Fig. 3 is a sectional view taken on the line 3—3 of Fig. 2;

45 Fig. 4 is a perspective view of the brackets supporting the induction coil;

Fig. 5 is a sectional view on line 5—5 of Fig. 2.

50 In the drawings a base of non-conducting material 106, adapted to be secured in an annular recess formed in a distributor head, is secured thereto by means of bolts 107 and 108 which pass through and make electrical connection with the coil brackets

109 and 110, and with the strips 55 and 56 respectively which serve as leads for the induction coil. Brackets 109 and 110 are secured upon base 106 by any well known means. Bracket 109 is provided with the up-turned ends 111, and bracket 110 with up-turned ends 112. It will be seen upon reference to Fig. 4 that bracket 110 is shorter than bracket 109, so that the ends 112 may be placed opposite ends 111, with spaces therebetween for the reception of insulation discs 113 (see Fig. 3). The ends 111 and 112 are provided with notches 114 for the reception of the coil assembly which will now be described. Said notches 114 are each provided with an enlarged portion spaced from the outer end of the notch.

55 The coil assembly consists of laminated core 115 surrounding the bolt 116. Upon the core are mounted primary windings 117, indicated by large squares, and the secondary windings 118, indicated by the small squares in Fig. 3. The ends of the coil are provided with insulating caps 120, carrying bushings 120^a, and outside of these caps are placed three pairs of laminated discs 121, 121^a, and 121^b provided with holes for the reception of the bushings. The purpose of these discs is to confine the magnetic field to the coil windings 60 as much as possible. Each disc is provided with a notch 122 extending from the periphery to the center to prevent formation of eddy currents, and to permit of the passage of bolt 116. Since it is highly desirable in aviation work where this distributor is adapted to be used, to keep down the weight so far as possible, it has been found that the discs more distant from the ends of the laminated core may be less in diameter 65 than those discs which are nearer, without any loss in efficiency in the provision 70 against losses in the magnetic field.

75 Insulation discs 113, centrally apertured for the reception of insulation spacers 123^b are centrally located with respect to the coil 80 by means of bushings 120^a which pass through diametrically opposite holes in said discs after the discs 113 have been placed on the bushings with spaces between them and the laminated discs 121^b, for the introduction of bracket ends 111 and 112. The brackets 109 and 110 having been assembled 85 on the base 106, the coil assembly is lowered 90

- into position on the brackets, the bracket ends 112 being inserted in the space between discs 121^a and the adjacent insulation discs 113, and bracket ends 111 being inserted in 5 the spaces between the discs 113. Bushings 120^a cooperate with recesses 114 of the bracket ends and locate the coil in proper position with respect to the brackets with bolt 116 located centrally of recesses 114.
- 10 This operation being completed, end plates 123 having dished portions 123^a around which are placed insulation spacers 123^b, are placed one on each end of bolt 116, and are pushed in toward the ends of the coil, the 15 portions 123^a with surrounding spacers 123^b seating in the recesses 114 of the brackets. The end plates 123 have flange portions which engage upon the outer discs 113. The 20 entire structure is clamped together by means of nuts 124 cooperating with bolt 116.

One end of the primary winding is connected by a wire 125 to bracket 110. The other end of the primary winding 126 and one end of the secondary winding 127 are 25 connected to the bracket 109. The other end of the secondary winding 128 is connected to a metallic button 129 mounted upon the center of the base 116. Button 129 is axially aligned with the distributor shaft and bears 30 at all times upon the spring 38 carried by the distributor rotor 28.

From the foregoing description it is apparent that the coil may be readily removed from its mounting brackets without removing 35 the brackets from the base. This feature is advantageous as the assembling of the coil on its base during the process of manufacture is facilitated, and it is a very simple matter to remove the coil for repairs 40 or replacement. The invention possesses the added feature of being adapted to be secured in position within a distributor head or other housing without the necessity of making any electrical "pigtail" connection 45 between the coil and its terminals located on the exterior of the head or housing.

While the form of mechanisms herein shown and described constitutes a preferred 50 form of embodiment of the invention, it is to be understood that other forms might be adopted, all coming within the scope of the claims which follow.

What we claim is as follows:

1. In an induction coil, the combination 55 with a coil assembly including a core; of a support therefor, including brackets of conducting material, each having means for supporting an end of the core of the coil assembly; and means for mechanically attaching said core to said brackets while insulating the brackets from one another.

2. In an induction coil, the combination 60 with a coil assembly, of a support therefor, consisting of two brackets, each comprising a central portion for mounting upon a base,

and upstanding end portions having apertures, so arranged that when the central portions are positioned upon a base, the end portions and apertures provided therein can be brought into alignment, said end portions 70 being provided with gaps between the end portions; and fastening members co-operating with the coil assembly and the apertured end portions for securing the coil assembly in position upon the end portions. 75

3. In an induction coil, the combination with a coil assembly consisting of a core and windings; of a support therefor, consisting of two brackets, each comprising a central portion for mounting upon a base, and upstanding end portions having apertures; a bolt extending through and projecting beyond the core; end plates carried by the bolt, having portions co-operating with the apertures in the bracket end portions; nuts on 80 the ends of the bolt for clamping the coil assembly, brackets, and end plates together, with the bracket end portions in alignment but not electrically connected, and holding bracket central portions in the same plane 85 for mounting upon a base.

4. In an induction coil, the combination with a coil assembly; of a support therefor including two brackets mounted upon a common base, and providing end supports 90 for the coil, each end support consisting of insulated portions, one of which is formed integrally with one of the brackets and the other formed with the other bracket; and means for securing the coil assembly 95 to the end supports.

5. In an induction coil, the combination with a coil assembly; of a support therefor including two brackets mounted upon a common base, and providing end supports 100 for the coil, each consisting of insulated portions, one of which is formed integrally with one of the brackets, and the other formed with the other bracket; aligned apertures in the end supports; end plates co-operating with the apertures but insulated from the end supports; and a common fastening means for securing the coil assembly 105 upon the end supports with the end plates seating within the apertures. 110

6. In an induction coil, the combination with a coil assembly having a core and windings; of laminated discs co-operating magnetically with the core, said discs decreasing in diameter outwardly from the 115 core.

7. In an induction coil, the combination with a coil assembly having a core and windings; of laminated discs co-operating magnetically with the core, said discs decreasing in diameter outwardly from the core; and aligned slots provided in the discs extending from the center outwardly to the periphery. 125

8. An article of manufacture including 130

a plurality of induction coil supporting brackets each having upstanding portions spaced apart substantially the length of an induction coil, and adapted to be assembled 5 with the said portions on the brackets in aligned positions with the portions at one end of the brackets in spaced relation.

9. In an induction coil assembly, the combination with an induction coil; of insulating plates; coil supporting members spaced apart substantially the length of the coil with the insulating plates between the members and coil; and means for clamping the plates and members against the ends of the 10 coil.

10. In an induction coil assembly, the combination with an induction coil; of supporting means on the ends of the coil; insulating plates on the ends of the coil; and 15 a bracket having laterally projecting apertured portions receiving the supporting means and adapted to embrace the coil and insulating plates.

11. In an induction coil assembly, the combination with an induction coil having a centrally located through bolt; of insulating plates on the ends of the coil; and 20

a bracket having laterally projecting apertured portions receiving the ends of the through bolt and clamped by the latter 25 against the insulating plates and ends of the coil.

12. In an induction coil, the combination with a supporting base; of a pair of coil brackets having V-shaped base portions secured to said supporting base, and having upturned end portions; and a coil assembly including a core having each end thereof mounted upon two upstanding bracket portions but insulated therefrom. 30

13. In an induction coil, the combination with a coil assembly having a core and windings; of laminated discs cooperating magnetically with the core, said discs having aligned slots extending from the periphery thereof. 35

In testimony whereof we affix our signatures.

WILLIAM A. CHRYSST.
JOHN H. HUNT.
